UNITED STATES PATENT OFFICE.

LEWIS W. HUBERTY, OF CANTON, OHIO.

DOOR-OPERATING DEVICE.

Application filed September 9, 1925. Serial No. 55,285.

This invention relates to door operating devices and has for an object to provide means for operating doors and more especially sliding doors, and still more especially 5 the doors of a garage or the like but not limited in its utility to any of said functions.

An object of the invention is to provide a door operating means which will automatically 10 from the same source of power open and close the doors with new and improved means for controlling the action of power for the purpose.

A further object of the invention is to 15 provide an apparatus driven from some source of power comprising winding drums which, when rotated in the proper direction, will either open or close the closures as occasion may make necessary or desirable and 20 also providing additional means for automatically reversing the action of continuous power for moving the doors from an attained to the opposite limit.

With these and other objects in view, the 25 invention comprises certain novel parts, elements, units, combinations, constructions, arrangements, interactions, mechanical movements and functions as disclosed in the drawings together with mechanical and function- 30 al equivalents thereof as will be hereinafter more fully described and claimed.

In the drawings:

Figure 1 is a conventional figure showing the utility of the present invention in operating oppositely sliding doors and receiving power from a conveniently located motor.

Figure 2 is a sectional view of the device taken in a vertical plane parallel with the 40 path of movement of the doors.

Figure 3 is a horizontal sectional view taken on line 3-3 of Figure 2.

Figure 4 is a vertical sectional view taken transverse to and on line 4-4 of Figure 2.

Figure 5 is a vertical sectional view taken on a plane transverse to and indicated by line 5-5 of Figure 2.

Figure 6 is a vertical sectional view illustrating one of the mechanical movements.

Like characters of reference indicate corresponding parts throughout the several views.

The improved door operating device which forms the subject matter of this ap-

plication comprises two units A and B, the 55 unit A being the unit for winding and unwinding the cable for operating the doors and taking power directly from the source of power, as the motor, while the unit B comprises means for shifting the belt from 60 the power to unit A at the limit of movement of the doors.

The doors, here shown as oppositely sliding doors C and D, are only shown for illustration and it is to be understood that, 65 while the device is capable of operating such oppositely and simultaneously sliding doors, it will likewise operate a single door or doors otherwise operated than as shown and that the invention is in no way limited by 70 the showing of the doors C and D. These doors slide in the type shown in the illustration upon the track E which is no limitation upon the invention and any type of 75 sliding doors or track for sliding doors is 75 within the scope of the invention. Likewise, as shown at Figure 1, a motor indicated as an electric motor F, is indicated as the source of power, but it is to be understood that, while such electric motor F is 80 desirable, it is in no way necessary to the invention and any means of applying power is within the scope.

From whatever source power is received, however, it is conducted through a belt 10 from such source to the unit A and upon the pulleys 11, 12 and 13. The pulley 11 is mounted rigidly upon the shaft 14 which is also rigidly connected with the winding drum 15. The pulley 13, through the medium of its hub 16, is rigidly connected with the winding drum 17, the shaft 14 passing through the pulley 13, hub 16 and drum 17 upon which shaft said member is free to rotate. The pulley 12 is an idler interposed 90 between the working pulleys 11 and 13 in the usual well known manner of loose pulleys. It is obvious that, if the belt 10 is shifted from the pulley 11 across the loose pulley 12 to the pulley 13, the power previously applied through the belt to the pulley 11 will be transferred to the pulley 13. The reverse movement will reverse this action.

The winding drum 15 is provided with 105 cables 18 and 19 which, when wound upon the drum 15, serve to move the doors C and D apart. The drum 17 is provided with

cables 20 and 21 which, when wound upon the drum 17, serve to move the doors C and D together. The operation of this part of the structure will be understood from the foregoing and that, when the belt 10 is shifted from one of the working pulleys to the other, the one drum will be released and the other drum operated so that by the shifting across of the belt 10, the action of the power from the source F will be reversed.

For the purpose of shifting this belt 10 at the limit of movement of the doors, the unit B is provided. This unit B comprises a roller 22 over which the belt 10 passes, bearing thereon with sufficient frictional engagement to rotate said roller as the belt moves. Beneath the roller 22 a worm 23 is journaled rotating from the roller 22 by means of a band 24 passing over a grooved pulley 25 upon the roller and a similar grooved pulley 26 carried by the worm 23. Beneath the worm 23 a similar worm 27 is journaled receiving power from the worm 23 through the medium of gears 28. As the roller 22 rotates under the action of the belt 10 passing thereover, the worms 23 and 27 rotate in opposite directions by reason of the intergearing at the gears 28.

Located in approximately horizontal relation to and in a plane intermediate the worms 23 and 27 are guide rods 29 and 30 upon which is mounted to slide a table 31 by the provision of ears 32. Beneath the guide rod 29 is a third guide rod 33 and a belt shifter comprising downwardly extending arms 34 slides upon the rods 29 and 30 and is connected with the table 31. This table 31 extends between the worms 23 and 27, as shown more particularly at Figures 2 and 4, and mounted thereon is a jack 35. The jack 35 carries upon its upper and under side respectively mutilated nuts 36 and 37 adapted, as the jack is raised or lowered, to engage respectively with the worms 23 and 27. Above the table 31 a guide rod 38 is mounted upon which moves roller 39 which supports a spring 40, the opposite end of which is connected with the jack 35 tending to raise said jack to hold the mutilated nut 36 in engagement with the worm 23.

At one side a cam 41 is located in such position that as the table 31 and jack 35 move to its position under the action of the worm, the cam forces the jack downwardly first out of engagement with the worm 23 and then into engagement with the worm 27. When the jack has been depressed, as shown at Figure 6, a roller 42 carried by the lever 43 is forced by the spring 44 to engage upon the top of the jack and hold it in its depressed position, that is to say in engagement with the worm 27. At the opposite limit of movement, a cam 45 is provided which engages the lever 43 and moves it to

the position shown at Figure 2, whereupon the spring 40 again acts to release the nut 37 from the worm 27 and engage the nut 36 with the worm 23.

In operation, assuming that the doors are at one limit of their movement as shown at Figure 1, the belt 10 would be in engagement with the pulley 13 and the lever 43 and roller 42 would be in the position shown at Figure 6 with the jack 35 depressed to bring the nut 37 into engagement with the worm 27. Power now applied to the pulley 13 will cause the cables 20 and 21 to be wound upon the drum moving the doors to closed position. Simultaneously, the belt 10 passing over the roller 22 will rotate the worms 23 and 27 so that the table 31 and its associated parts will move entirely from one end of the worms to the other. The movement of this table 31 and its associated parts will shift the belt 10 from operative engagement with the pulley 13 to engagement with the pulley 11, over run being taken advantage of in the usual well known manner. Upon the movement of the table and its associated parts to the opposite extreme of movement, the cam 45 will engage the lever 44 and move it to the position shown at Figure 2 whereupon the spring 40 will throw the jack 35 from the position shown at Figure 6 to the position shown at Figure 2 and the parts are now ready to reverse and open the doors at the next operation. From this point the cycles of operation will be fully understood and further description would only add to the record.

What I claim to be new is:

1. The combination with adjacently journaled pulleys and a belt adapted to actuate either of said pulleys electively, a roller upon which one section of the belt operates, a pair of adjacent worms journaled transversely of the belt and intergeared to rotate in opposite directions and driven from the roller, a member introduced between and mounted to move longitudinally of the worms, nut sections carried by said member adapted to separately engage with the worms, means at opposite extremes of travel of the member to shift the member to release the engaged nut section and engage the free nut section, and means carried by the member to shift the belt in its movement.

2. The combination with adjacently journaled pulleys and a belt adapted to actuate either of said pulleys electively, a roller upon which one section of the belt operates, a pair of adjacent worms journaled transversely to the belt and intergeared to rotate in opposite directions and driven from the roller, a guide mounted in parallelism with the worms, a member introduced between the worms and mounted to slide longitudinally upon the guide, nut sections carried by said member adapted to separately engage with

the worms, means at opposite extremes of travel of the member to shift the member to release the engaged nut section and engage the free nut section, and means carried by the member to shift the belt in its movement.

3. In combination with adjacently journaled pulleys and a belt adapted to actuate either of said pulleys electively, a roller upon which one section of the belt operates, a pair of adjacent worms journaled transversely to the belt and intergeared to rotate in opposite directions and driven from the roller, a pair of guides mounted upon opposite sides of and in parallelism with the worms, a member introduced between the worms and mounted to move longitudinally upon the guides, nut sections carried by said member adapted to separately engage with the worms, means at opposite extremes of travel of the member to shift the member to release the engaged nut section and engage the free nut section, and means carried by the member to shift the belt in its movement.

4. The combination with adjacently journaled pulleys and a belt adapted to actuate either of said pulleys electively, a roller upon which one section of the belt operates, a pair of worms journaled transversely of the belt and intergeared to rotate in opposite directions and driven from the roller, a member introduced between and mounted to move longitudinally of the worms, nut sections carried by said member adapted to separately engage with the worms, a spring tending to hold the member with one nut section in engagement with one of the worms, means at one extreme of travel of the member to move the member against the tension of the spring, to disengage the engaged nut section and engage the free nut section, a latch to hold said member in said last assumed position, means at opposite extreme of travel to release said latch, and means carried by the member to shift the belt in its movement. 25 30 35 40 45

In testimony whereof I affix my signature.

LEWIS W. HUBERTY.
